SEARCHED

UNITED STATES PATENT OFFICE.

WILFRID DORION, OF CHARLESBOURG, QUEBEC, CANADA.

MEANS TO CHANGE THE SPEED OF DRIVING-PULLEYS.

1,353,153.

Specification of Letters Patent. Patented Sept. 21, 1920.

Application filed January 16, 1919. Serial No. 271,420.

To all whom it may concern:

Be it known that I, WILFRID DORION, residing at Gros Pin, Charlesbourg, in the Province of Quebec, in the Dominion of Canada, have invented certain new and useful Improvements in Means to Change the Speed of Driving-Pulleys; and I do hereby declare that the following is a full, clear, and exact description of the same.

10 The present invention relates to improvements in a means to change the speed of a driving pulley, and is here shown as adapted to a motorcycle not fully illustrated in the drawings.

15 The main object of the invention is to provide a simple, efficient and comparatively inexpensive means of varying the speed imparted by a driving belt.

20 The present invention consists in the combination and arrangement of parts with a shaft, of three pulleys of different diameters sliding one over another, all being connected together on the same shaft and operated by a single lever whereby they can 25 be shifted into operation one after the other and shifted out of operation all simultaneously by the same lever.

25 The invention will hereinafter be fully explained in the following description and 30 accompanying drawings in which:

Figure 1 is a front elevation of the invention and operating mechanism, illustrating only a portion of the motorcycle, the pulleys being shown in their inoperative position.

35 Fig. 2 is a front elevation of the invention and mechanism in its operative position.

Fig. 3 is a side elevation of the invention.

40 Fig. 4 is a side elevation of one of the pulleys.

Fig. 5 is a front elevation of the pulley shown in Fig. 4.

Fig. 6 is a side elevation of the larger pulley.

45 Fig. 7 is a front elevation of the pulley shown in Fig. 6.

Fig. 8 is a front elevation of the main driving pulley.

50 Fig. 9 is a side elevation view of the pulley illustrated in Fig. 8.

Like numerals of reference indicate corresponding parts in each figure.

In the drawings, 1 is a portion of a motorcycle frame, 2 is the motor and 3 is the crank shaft.

55 On one end of the crank shaft 3 is rigidly mounted the main driving pulley 4, preferably of small diameter, which is provided with the upwardly projecting sides or guides 5 and inclined inner sides 6; and 7 are 60 slots in the said pulley 4 in which the pulley 8 slides.

65 The pulley 8 is preferably larger in diameter than the pulley 4. This pulley has a drum-like shape and is provided with lateral grooves 9 and oblique lugs 10 projecting therefrom which are adapted to slide on the pulley 4 and support the pulley 8. The pulley 8 will be hereinafter 70 called the medium pulley.

75 The grooves 9 and lugs 10 correspond to the slots 7 in the pulley 4 so that the medium pulley 8 will entirely fit within the sides 5 of the small pulley 4 as disclosed in Fig. 2. The medium pulley 8 has on one end a sleeve 11 which fits over the shaft 3 and 12 is a circular groove in which fits the sleeve 13 and 14 is a forked rod pivotally engaging lugs provided on said sleeve 13.

80 Slidable over the medium pulley 8 is provided a pulley of larger diameter 15 hereinafter called the large pulley, of practically similar shape to the medium pulley 8. This larger pulley has a sleeve 16 which is 85 slidable on the sleeve 11 of the medium pulley 8 and 17 are lateral slots corresponding to the slots 7 in the small pulley 4, so that this large pulley may fit within said pulley together with the medium pulley 8 as disclosed in Fig. 2 of the drawings.

90 The lateral slots 17 are so made as to engage the guide lugs 18 projecting from the medium pulley 8.

95 On the outer end of the sleeve 16 is provided a circumferential groove 19 and 20 is a rod forked at one end and adapted to pivotally engage the lugs provided in a collar or sleeve 21 which is provided in said groove 19.

100 A bracket 22 is secured on said motor and projects outward, and on its outer end is secured a stub shaft 23.

The rod 14 is pivotally mounted on said shaft 23. The rod 20 is also pivotally

mounted on said stub shaft 23 and projects beyond said shaft at an angle and '24 is a hand lever pivotally secured at 25 and pivotally connected at its other end to the rod 20. On the frame 1 is provided a bracket 26 suitably notched to lock the said lever in position. Adjacent the shaft 23 is provided a flat spring 27 which is adapted to rest against the rod 14.

Secured on the rod 20 is a guide member 28 preferably slotted and through which passes the rod 14 so that it will be carried forward, when the rod 20 is operated.

In the operation of the invention, it will readily be seen that on operating the hand lever 24, the rod 20 will be pushed forward carrying with it the pulley 15. The guide 28 which is secured to the rod 20 will pull the rod 14 and pulley 8, so that when the hand lever is pulled into the middle notch in the bracket 26, the pulley 8 will enter the main driving pulley 4. On further pulling the hand lever into the next notch, the pulley 15 will be carried over the pulley 8 increasing the diameter of the main driving pulley 4. By reversing the operation, the

pulleys 8 and 15 will be pulled back into their inoperative position.

What I claim as my invention is:

A device of the character described, comprising a driving pulley mounted on a driving shaft, said pulley having a plurality of slots therethrough, a medium pulley having a plurality of projections adapted to register with the slots in said driving pulley, said medium pulley being loosely mounted and slideable on said shaft adjacent said driving pulley, a large pulley loosely mounted and slideable on said shaft adjacent said medium pulley, said large pulley having a plurality of projections adapted to register with the slots in said driving pulley, a hand lever, rods connecting said medium and large pulleys to said lever, and means to cause said medium and large pulleys to saddle said driving pulley when said lever is operated substantially as described.

WILFRID DORION.
